UNITED STATES PATENT OFFICE.

JOEL R. COOK, OF LAKewood, OHIO, ASSIGNOR TO THE DOMESTIC ELECTRIC COMPANY, OF CLEVELAND, OHIO, A CORPORATION OF OHIO.

CENTRIFUGAL MOTOR SWITCH.

Application filed August 5, 1922. Serial No. 579,789.

To all whom it may concern:

Be it known that I, JOEL R. COOK, a citizen of the United States, residing at Lakewood, in the county of Cuyahoga and State of Ohio, have invented a certain new and useful Improvement in Centrifugal Motor Switches, of which the following is a full, clear, and exact description, reference being had to the accompanying drawings.

10 This invention is directed to improvements in centrifugal switches such as are used in small induction motors for cutting out an auxiliary set of field windings which are used for starting purposes only.

15 The general object of the present invention is the provision of a switch mechanism having pivotally mounted contact elements supported on the rotor of the motor which are maintained in engagement with stationary contacts secured to the motor frame during the starting and preliminary period in which the increase in the speed of the rotor is approaching a predetermined point and which are acted upon and raised out 20 of engagement with the stationary contacts at a predetermined point in the acceleration of the speed of the motor. The elements 25 acted upon by centrifugal force are of a simple design and formed of compressed 30 metal.

A more specific object of the present invention is the provision of a centrifugal switch wherein a plurality of rotatable contact arms are provided which are pivotally secured to a support; the contact arms being formed of comparatively thin metal but shaped in such a manner as to provide in effect unusually wide bearing portions to insure a uniform and simultaneous movement of all of the arms when the rotor has reached a predetermined speed, the whole being so designed as to be almost entirely manufactured in high production by stamping and pressing operations and be capable 45 of great uniformity for convenience in assembling.

50 A further object is the provision of rotatable contact elements having the foregoing characteristics and in addition thereto having the various portions thereof arranged in such a manner, relative to the pivotal point of the arms, that resilient members connected to the arms and the support, may normally maintain the arms 55 in an inward contacting position, but which,

when swung outwardly by centrifugal force, cause a decrease in that component of force of the spring members, which is directed to maintaining the arms in an inward position, thus causing the arms to close inwardly at 60 a speed of rotation considerably less than the speed at which they are swung outwardly by centrifugal force.

65 A further object is the provision of a centrifugal switch mechanism which will effectively fulfill the foregoing objects and which may be so constructed as to occupy a minimum of space within the motor frame.

70 Other objects will be apparent from the following description taken in connection with the accompanying drawings, which illustrate an embodiment of my invention; the essential objects will be summarized in the claims.

75 In the drawings, Fig. 1 is a side elevation of the motor with a portion thereof shown in cross section to illustrate the relative position of the switch mechanism; Fig. 2 is a cross section of the switch mechanism taken along the line 2—2 of Fig. 1, showing the switch mechanism in a starting or closed condition; Fig. 3 is a similar view showing the relation of the movable parts of the switch mechanism after the switch 80 has been opened by centrifugal force; Fig. 4 is a side view of the movable parts of the switch, and Fig. 5 is a perspective view of one of the contacting elements of the switch. 85

90 1 indicates a motor housing having an integral base 2 and supporting the field structure 3. The frame members 4 are secured to the housing 1 by suitable bolts (not shown) and are provided with bearings, as indicated at 5, which support the armature shaft 6. Secured to one of the frame members 4 and disposed within the housing is an insulating disc 6 which constitutes a support for non-rotatable segments 8, properly flanged to permit the securing thereof to the disc member 6. To 95 these non-rotatable segments are connected lead wires 11 and 12 which comprise a part of the circuit of the starting winding S as shown in Fig. 2. This circuit may be attached to the field circuit 14 in such a manner as to connect the field windings F, through the switch when closed in parallel with the starting windings S. 100

105 The rotatable elements of the switch 110

mechanism comprise a metallic disc member 18 mounted on one end of the rotor 19 and secured thereto by screw members 40 which are suitably insulated, as illustrated in Fig. 1, by fibre washers 22 and 24.

Pivots mounted upon the disc member 18 are swingable members 20, preferably three in number, which have brush or contacting portions 21 arcuately formed thereon, so as to afford considerable contacting area with the non-rotatable segments 8. These arms are supported on pin members 23 rigid with the disc member 18 and are positioned equiangularly thereon, and at equal distances from the center of rotation of the shaft. Spring members 25 are connected to outwardly extending lugs 26 formed about the perimeter of the disc member 18 and to the contacting arms 20 in a manner to be presently described. It will be noted that these lugs likewise comprise stops for positively limiting the outward swing of the contact arms 20.

The contact arms 20 are preferably stamped, as illustrated in Fig. 5, with the contact portion 21 extending from the arm portion substantially at right angles thereto, and formed adjacent the free end of the arm. The bearing portion of the arm 25 may comprise a U-shaped end with aligned openings 28 and 29 formed in the legs 20 and 30 thereof whereby a double bearing contact is obtained when the contact arm is mounted on the pin members 23. The distance between the legs of the U portion of the arm may be such as to provide a sufficient span between the bearing portions of the arm when mounted on the pin, to prevent wobbling of the arm as it is swung about the center of the pin by centrifugal force. By this bearing arrangement I gain the advantages, of a solid bearing portion having a bore and opening formed in the solid metal equal to the overall distance 45 between the bearing portions of the present arm, and at the same time having less friction, less weight, and I effect an economy of material and in the steps of construction.

In forming the bearing end of the contact arm in the manner described, a portion 50 31 which bridges or spans two bearing portions of the arm may have an opening 32 formed therein intermediate of these bearing portions. When the contact arm is mounted on the pins 23 this opening will be in alignment with an opening 26^a formed in an extended portion of the lug 26 and the ends of the spring members 25 may be connected or hooked into the respective 55 openings whereby the center line of the spring will be parallel to the supporting disc 18. To facilitate the assembling of the end member 4 when the stationary segments 8 are secured thereto, the contacting portion 60 of the arms 20 may have the outer ends

thereof slightly flared outwardly and the inner end 8^a of the segments may be turned inwardly whence the segments will have a wedging or spreading effect upon the arms during this assembling operation. To prevent the spring members 25 from moving the contact arms inwardly beyond the position where the contacting portions thereof would not be spread by the segments, in the assembling operation mentioned, I have provided lug members 35 formed about the inner perimeter of the disc member 18 against which the arms are held in an inward position by the spring members 25 when the segments 8 are not in assembled 70 relation to the contact arms but still sufficiently separated to allow convenient insertion of the segments by simply sliding one over the other.

It will be noted that the effective component pull of the spring on the lever is decreased as the arms swing from the contacting position to the open position. The result of this change in the component of spring pull upon the arms is that the switch 85 mechanism opens at a high speed which is predetermined by the size of the springs used but the contact arms will not be brought to a closed or contacting position until the rotation of the motor armature is 90 considerably below the speed at which the contact arms moved outwardly. The period in which the contact arms is rubbing upon the stationary segment is thereby greatly reduced.

From the foregoing description, it will be seen that I have provided a very simple, yet efficient centrifugal switch construction wherein a plurality of arms of the same shape and formed of pressed metal are 105 mounted upon a pressed metal disc; the contact portions of the arms being formed to provide extraordinary contact or running surfaces yieldably bearing upon stationary segments which are also formed of 110 pressed metal. The thickness of the rubbing part being sufficient to allow for considerable weight, thus preventing the rapid deterioration of the switch, due to arcing and corroding of the contacting parts.

I claim:—

1. In a centrifugal switch, the combination of a rotary support, a stationary contact, a plurality of contact arms pivotally mounted upon the support and spaced equiangularly thereon, the pivotal center of the arms being spaced at equal radial distances from the center of rotation of the switch, said contact arms having U-shaped bearing portions comprising the pivotal mountings 120 thereof and spring members connected to said arms intermediate the legs of the U-shaped portions and connected to equiangularly spaced lugs formed on said rotary support.

2. In a centrifugal switch, the combination of a rotary support, a stationary contact, a plurality of contact arms pivotally mounted upon the support and spaced equi-
5 angularly thereon, said contact arms having parallel portions spaced apart and spring members connected to said arms intermediate said parallel portions and connected to lugs formed on said rotary support.
- 10 3. In an electric motor, a centrifugal switch having a rotary support mounted on one end of the rotor and a stationary contact segment mounted on an end housing member of the motor, said centrifugal switch having a plurality of coacting contact arms pivotally mounted upon said rotary support, spring members connected to the ends of the contact arms and to the
15 rotary support, whereby the free ends of the contact arms are maintained in contact with said stationary segments, said contact arms having the contacting portions thereof flared outwardly, and said contact segments having the ends thereof flared inwardly whereby the end housing member of the motor frame may be assembled upon the frame with the stationary segments mounted thereon, the flared portions of the
20 30 respective switch members contacting with the flared portions of the segments in such a manner as to cause an outward movement of the contact arms when the end member is being attached to the motor frame.
- 35 4. In a centrifugal switch, the combination of a rotary support, stationary contacts, and a plurality of coacting contacting arms pivotally mounted on the rotary support and proportioned relative to the pivotal connection to swing outwardly under the influence of centrifugal force at a predetermined speed of the rotor, said contact arms being formed of pressed metal with U-shaped portions having the legs thereof
40 perforated to provide a pivotal connection with the support, pivot pins passing through said openings and spring members connected to the arms intermediate said legs.
5. In a centrifugal switch, the combination of a rotary support, a stationary contact, a plurality of contact arms formed of pressed metal with arcuate brush portions engaging said stationary contact, each arm being independent of the other and having parallel extending portions, pivot pins passing through said parallel portions of the arms and rigid with the support, resilient means connected to said arms and the support, the connecting point of the resilient means with the arm being located relative to the pivotal axes thereof in such a manner that the component force exerted thereby upon the arms to maintain the arms inwardly will be decreased as the arm is swung outwardly under the influence of centrifugal force.
6. In a centrifugal switch, the combination of a rotary support comprising an apertured disk provided with a plurality of equi-angularly spaced lugs formed about the outer perimeter thereof and a plurality of lugs formed about the inner perimeter thereof, a plurality of pressed metal contact arms, a stationary contact comprising two elements in the nature of a split flanged cylinder, resilient means normally maintaining the arms in operative relation to said stationary contact, said inner lugs serving to limit the inward movement of the arms in the absence of the stationary contacts and the outer lugs serving to limit the outward movement of the arms when swung outwardly by centrifugal force.
- In testimony whereof, I hereunto affix my signature.

JOEL R. COOK.
